UNITED STATES PATENT OFFICE

JOHN Q. SHERMAN, OF DAYTON, OHIO

SEPARATOR FOR MANIFOLDING MATERIAL

Application filed September 28, 1931. Serial No. 565,590.

This invention relates to typewriters, and more particularly to means for separating the interleaved strips of manifolding material from the record strips preparatory to the separation of completed sheets from the supply strips in the use of continuous series connected stationery.

The use of "one time" carbon with continuous series connected stationery wherein the strips are transversely scored or perforated for separation at spaced intervals has become quite common. To facilitate the separation of the manifolding material from the record sheets after detachment from the supply strip, finger tabs are frequently provided upon the carbon material which project beyond the transverse tear line or division line. Due to the tenacious surface of the interleaved carbon material, such material after passing about the platen roll of the typewriter it is inclined to adhere to the record strip, and by the binding action incident to twisting motion in tearing off the completed portion of the strip, the finger tabs are gripped between the record sheets and are sometimes accidentally torn, thereby defeating their subsequent use in separating the detached sheets.

The present invention pertains to separating fingers mounted upon the typewriter and projecting between the strips of record and transfer material as they pass from the typewriter platen roll, with means for relatively separating such fingers to spread or separate the strips preparatory to the detaching operation.

The object of the invention is to provide a simple and inexpensive means applicable to standard typewriters for facilitating the preliminary separation of the transfer material from the record strips preparatory to detachment of the written sheets and thereby preserving intact the finger grips provided for subsequent separation of the detached sheets.

A further object of the invention is to provide a simple device which will not interfere with the normal operation of the typewriter or other manifolding apparatus, and which may be easily and quickly operated.

With the above primary and other incidental objects in view, as will more fully appear in the specification, the invention consists of the features of construction, the parts and combinations thereof, and the mode of operation, or their equivalents, as hereinafter described and set forth in the claims.

Referring to the accompanying drawing, wherein is shown the preferred but obviously not necessarily the only form of the embodiment of the invention, Fig. 1 is a perspective view of a conventional typewriter to which the present invention has been applied. Fig. 2 is a detail perspective view of the typewriter platen viewed from the rear illustrating the relative location of the present separating fingers. Fig. 3 is a detail perspective view of the separator attachment removed from the typewriter showing the parts in their normal or idle position. Fig. 4 is a detail view showing the separator fingers in their operative relation. Fig. 5 illustrates a modification.

Like parts are indicated by similar characters of reference throughout the several views.

Referring to the drawing, 1 is a conventional form of typewriter of which 2 is the platen roll and 3 and 3a indicate superposed strips of manifolding material of which the strips 3 are the record strips and the strips 3a are the interleaved strips of carbon or transfer material. The latter are provided with finger tabs 4 coincident with the transverse tear off or division line by which the interleaved carbon sheets may be separated from the record sheets after detachment from the strips. The tabs may be disposed either marginally or medially of the transfer strips.

Mounted upon the typewriter carriage at opposite sides of the platen roll 2, are supporting brackets 5-5 in which is journaled a rock shaft 6. Mounted concentrically thereof at the end of the rock shaft 6 contiguous to the tabbed margins of the manifolding strips are a plurality of rock arms 7a, 7b and 7c, each having a laterally extending finger 8 of quite thin material which projects intermediate the superposed record and manifolding strips as the latter passes from the platen.

roll 2. The rock arm 7a is fixedly secured to the rock shaft 6. The arm 7c is fixedly secured to the supporting bracket 5. The intermediate arm or arms 7b are loosely journaled on the shaft intermediate the arms 7a and 7c. The several arms are interconnected with each other for limited relative movement whereby the arms progressively interengage upon rocking motion of the shaft to effect a "fanned" or divergent relation wherein the separating fingers 8 are spaced one from the other thereby relatively separating the carbon material from the adjacent record strips to which it might otherwise ad-

5 here.

10

15

The fanned relation of the arms may be variously effected by different forms of interconnection of the arms.

A convenient form of such connection is 20 to provide a slot 8a in each succeeding arm in which engages a stud 9 in the preceding arm. The slot permits a limited independent movement of one arm before the stud engages with the end of the slot whereupon 25 the second arm will then move in unison with the first arm until the end of the slot 8a and stud 9 pertaining to the succeeding arms come into engagement, thus transmitting movement to the succeeding arm. The 30 engagement of the final slot and stud, one of which is carried by the stationary arm 7c serves to limit the adjustment of the arms and movement of the rock shafts.

In lieu thereof the arms may have concentric hubs 10, each having therein a notch 11 35 of divergent circumferential extent. A stud 12 in the rock shaft projects within registering portions of the notches, and as the shaft is rotated the stud engages first with one and 40 then the other of the notched hubs, moving the first hub and connected arm a limited distance before engaging the second hub to move the second arm in unison.

The rocking motion of the shaft 6 to effect 45 such "fanned" separation of the arms 7 is effected by a finger operating lever 13 at the opposite end of the rock shaft 6 operating against a retracting spring 14 interposed between the operating lever 13 and the supporting brackets 5.

There is also provided upon the rock shaft 6 a further rock arm 15 fixedly secured to the shaft and carrying a contact head 16 overhanging the platen roll 2 and effecting a pressure contact with the manifolding material 55 upon oscillation of the rock shaft, to grip and hold the manifolding material while the written portions of the strips are detached upon the transverse division lines. The several strips being held apart adjacent to the final end of the tear lines at which the finger tabs are located, and the supply portions being clamped by the arm 15, the used portions of the sheets will be detached upon the trans- 60 verse tear lines and then around the finger

tabs without mutilating the latter due to binding or to its adherence to the record strip which is torn on a straight line without the finger tag deviation. The device therefore is of duo-functional character serving to fixedly hold the unwritten portion of the manifolding material relative to the platen roll while the finished portions are being detached and simultaneously separating the strips to prevent binding of the finger tab portion by twisting the forms during detachment or adherence thereof to the adjacent record strips and so preventing accidental mutilation.

70 From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

75 While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

80 Having thus described my invention, I now claim:

1. A device for separating superposed strips of manifolding material being fed through a writing machine, comprising a plurality of relatively movable fingers projecting intermediate the superposed strips, and actuating means common to the fingers for moving each finger a limited distance independently of succeeding fingers and by further movement thereof moving succeeding fingers in unison therewith.

85 105 110 115 120

2. A device for separating superposed strips of manifolding material being fed through a writing machine, including a plurality of relatively movable fingers projecting intermediate the strips, and adjusting means common to the fingers for separating the fingers into spaced relation with each other, to thereby separate the strips of manifolding material preparatory to detachment of portions thereof.

3. A device for separating superposed strips of manifolding material being fed through a writing machine, including a plurality of relatively movable fingers projecting intermediate the strips, a clamp member for holding the supply portions of the strips immovable, actuating means common to the separator fingers and to the clamp member for simultaneously operating the clamp member 125 130

- into clamping engagement with the superposed strips and spreading the fingers relative to each other to separate the strips beyond the point of engagement of the clamp member preparatory to detachment of used portions thereof. 5
4. A device for separating superposed strips of manifolding material being fed through a writing machine, including a plurality of relatively movable fingers projecting intermediate the strips, means for progressively spreading the fingers to separate the strips one from another, and a clamp member engageable with the strips beyond 10
- 15 the separated portions thereof as the fingers approach the limit of their spreading movement to hold the supply portions of the strips preparatory to detachment of the spread used portions thereof. 15
- 20 5. A device for separating superposed strips of manifolding material being fed through a writing machine, including a plurality of relatively movable fingers projecting intermediate the strips, a rock shaft for 25 actuating the fingers progressively engaging coupling means for actuating the fingers in succession by the partial rotation of the rock shaft to spread the fingers and therewith the strips preparatory to detachment of used portions thereof. 30
6. A device for separating superposed strips of manifolding material as they pass through a writing machine, including a plurality of rock arms, fingers carried by the respective arms and projecting between succeeding strips, lost motion connections between succeeding arms of the plurality, and means for progressively actuating the arms, each arm being capable of limited initial 35 movement independently of succeeding arms which upon further movement of the preceding arm are moved in unison therewith. 40
7. A device for separating superposed strips of manifolding material as they pass through a writing machine, including a plurality of rock arms, fingers carried by the respective arms and projecting between succeeding strips, a rock shaft upon which the arms are mounted, and intercoupling means 45 for progressively oscillating the arms by rotation of the shaft to spread the fingers and therewith the strips preparatory to detachment of used portions thereof. 50
8. A device for separating superposed strips of manifolding material as they pass through a writing machine, including a plurality of relatively movable fingers extending between the superposed strips, a clamp member for holding the supply portions 55 of the strips immovable, and a common actuating means for spreading the fingers and therewith the engaged strips and operating the clamping member into engagement with the strips preparatory to detachment of used 60 portions of the strips. 65
9. A device for separating superposed strips of manifolding material as they pass through a writing machine, including a plurality of relatively movable fingers extending between the superposed strips, and normally in closely disposed relation, and actuating means common to the plurality of fingers for spreading the fingers and therewith the engaged strips preparatory to detachment of used portions thereof. 70
10. A device for separating superposed strips of manifolding material as they pass through a writing machine, including a plurality of relatively movable fingers extending between the superposed strips, and actuating means for alternately expanding and contracting the plurality of fingers and likewise the engaged strips at the will of the operator. 75
- In testimony whereof, I have hereunto set my hand this 11th day of September, A. D. 1931. 80
